UNITED STATES PATENT OFFICE

HENRY H. OLSEN, OF DETROIT, MICHIGAN, ASSIGNEE TO THE AUTOFONT COMPANY, OF DETROIT, MICHIGAN, A CORPORATION OF MICHIGAN

MAGAZINE CUP DISPENSER

Application filed March 8, 1930. Serial No. 434,212.

My invention relates to cup dispensers and concerns particularly the association with a dispenser of an accessory in the form of a magazine structure for supporting reserve stacks of internested cups and for automatically, under control of the dispensing operation, depositing a reserve stack in the dispenser when the cup supply in the dispenser reaches a certain predetermined minimum.

An important object of the invention is to provide a simple, compact, yet large capacity magazine structure which can be readily applied to and associated with existing types of cup dispensers.

A further object is to provide a stationary magazine arranged to support a horizontal row of reserve stacks of cups, and propulsion means on the magazine structure for shifting the row of cup stacks to bring the end stack into position where it may drop by gravity into the dispenser.

A further object is to have the operation of the propulsion means on the magazine structure independent of the power which actuates the cup dispensing mechanism of the cup dispenser, but to release such propulsion mechanism for operation by the movement of the dispensing controlling mechanism.

A further object is to provide propulsion mechanism which is spring actuated but normally held in restraint by stop mechanism, together with mechanism operated during movement of the cup dispensing mechanism for setting the stop mechanism to permit shifting of the row of reserve stacks by the propulsion mechanism a distance sufficient to cause deposit of the end stack into the dispenser.

A still further object is to provide means whereby the number of cups in the dispenser determines the effective operation of the stop setting mechanism.

The above enumerated and other features of the invention are incorporated in the structure disclosed on the drawings, in which drawings

Figure 1 is a side elevation of a cup dispenser and a magazine structure associated therewith;

Figure 2 is a plan view of the dispenser and magazine structure;

Figure 3 is an enlarged plan view of the dispenser and the mechanism thereon for controlling the setting of the escapement mechanism; and

Figure 4 is an enlarged side elevation of the dispenser showing the escapement setting controlling mechanism.

I have shown my improved magazine applied to a well known type of drinking cup dispenser, as for example, a dispenser such as disclosed in Luellen Patent 1,261,950, issued April 9, 1918. Briefly, the dispenser shown comprises a supporting frame having the rectangular body 1 through which extends the circular dispensing passage 2. Mounted on a ring 3 surrounding and concentric with the opening 2 are the dispensing elements 4 whose ribs 5 project into the opening 2 for cooperation with the flanges 7 of cups 8 to be dispensed. A lever 9 extends from the ring 3 and when this lever is swung horizontally the ring is rotated and the escapement elements 4 are reciprocated so that their ribs 5 will cause the one-by-one dispensing of cups from the lower end of the cup stack disposed in the dispenser, the lower end of the stack projecting into a skirt 10 depending from the frame body 1, through which skirt the dispensed cup is guided to be received by the hand or to be deposited upon a suitable support to be filled with a liquid dispensed from a dispensing machine with which the cup dispenser may be associated.

The dispenser body 1 may also be provided with an annular vertical flange or extension 11 for guiding the stack of cups to the dispensing passage 2.

The magazine structure framework comprises transverse end bars 12 and 13 connected together by parallel guide rods 14 and 15. As shown, these guide rods are threaded at their ends to extend through the bars and receive nuts 16 for securely clamping the bars and rods together. Between the ends of bars 12 and 13 extends a longitudinal flat bar 17 which is secured at its ends to the

end bars and assists the rods 14 and 15 in forming a rigid supporting frame work.

The rear ends of the walls 12 and 13 are deflected inwardly to form brackets 18 by means of which the supporting framework may be secured to a supporting wall, and an additional bracket structure 19 may be extended from an intermediate point of the longitudinal bar 17 to assist in supporting the framework and in holding the bar horizontal.

Mounted to slide along the guide rods 14 and 15 is a pusher structure P. The structure shown comprises the U-shaped runner members 20 and 21 whose legs have openings for receiving the rods 14 and 15 respectively. These runner members 20 and 21 are connected together by transverse plates 22 and 23 which between the runner members support the bar 24 which at its inner end has the upwardly projecting extension or arm 25, the bar 24 and the arm 25 being above and in alignment with the longitudinal frame bar 17.

25 Near the inner end of the magazine structure a bracket 26 extends downwardly from the bar 17 and supports the housing 27 in which is journalled the roller 28 for a propulsion band or ribbon 29. The ribbon is guided around the rounded corner 26' of the bracket 26 and extends through an opening 30 in the bar 17 and then along the top of the bar and below the bar 24 of the push structure P, the end of the ribbon being then secured to a clip 31 fastened to the outer end of the bar 24 by a screw 32. A suitable spring 28' connects with the roller 28 and tends to rotate it to cause the exertion of tension or pull on the ribbon 29 and this pull of the ribbon on the push frame P tends to slide this frame inwardly along the guide rods 14 and 15.

45 Provision is made for the step by step advancement of the pusher structure P along the guide rods. This is accomplished by means of escapement fingers extending from an escapement shaft 33 journalled in the front ends of the walls 12 and 13 to extend parallel with the rods 14 and 15. Supported on the ribbon 29 and the bar 17 in front of the abutment arm 25 of the pusher structure is a row of stacks S of cups to be charged into the dispenser in a manner to be presently explained. I have shown five stacks and I therefore provide five abutment fingers a, b, c, d, and e on the escapement shaft 33. As clearly shown in Figures 1 and 2, these fingers are consecutively offset 45° circumferentially on the shaft 33 and when the magazine is fully loaded the finger a will project horizontally inwardly to be in front of the runner member 20 of the pusher structure so as to hold this structure at the outer end of its travel against the pull of the ribbon 29 by the spring actuated roller. A 45°

rotational movement of the shaft 33 will swing the finger a downwardly to release the pusher structure for advancement by the ribbon, but such rotational movement has brought the escapement finger b into horizontal position into the path of the pusher structure which will be stopped by its engagement with the finger b. The next 45° rotation of the shaft 33 will release the finger b from the pusher structure which can then advance until it strikes the abutment finger c which will have been brought into stopping position, and so on. Thus the pusher structure may advance step by step, and during such advancement the row of reserve cup stacks is shifted inwardly.

The cup dispenser and the magazine structure may be secured together or the dispenser and the magazine structure may be secured to a common support with the inlet to the dispenser in alignment with the row of reserve cup stacks on the magazine structure. Each advancement of the pusher structure will then cause the end stack to be brought into vertical position above the dispenser inlet so that the stack may drop into the dispenser.

The escapement operation for releasing the pusher structure for advancement is controlled automatically during operation of the dispensing lever 9 and at a time when the supply of cups in the dispenser reaches a certain predetermined minimum. To facilitate movement of the end stack into position over the dispenser, a guide plate 34 is mounted on the inner end of the bar 17 to receive the stacks from the ribbon 29 as the stack row is shifted inwardly. The ends f and g of the guide plate are beveled and the end g deflects diagonally downwardly a distance to assist in guiding the end stack into proper alignment with the dispenser. To prevent tampering with the magazine structure it may be enclosed by a suitable housing 35 whose inner section 35' may be semi-circular to receive the end cup stack discharged from the magazine to hold it in vertical alignment and guide it into the dispenser.

Describing now the escapement operation controlling mechanism, a bracket 36 secured to the front side of the body 1 of the dispenser journals a horizontal shaft 37. Secured to this shaft is an arm 38 which extends upwardly and carries a flexible contact member 39 in the form of a spring bar which has its end 40 deflected downwardly. At its outer end the shaft 37 supports a weighted lever 41 extending horizontally inwardly and supporting an arm 42 which at its inner end is extended and diagonally deflected to form a cam wing 43. The weighted lever 41 tends to swing downwardly to rotate the shaft 37 and to swing the arm 38 inwardly to carry the contact spring end 40 radially across the top of the dispenser. When the cup stack in

the dispenser projects above the level of the spring end 40 such swing of the arm 38 will be prevented by the abutment of the spring end against the side of the stack. However, as soon as the stack in the dispenser diminishes and drops below the spring end level, the spring end will be free and then the weighted lever will cause rotation of the shaft 37 and inward swing of the arm 38.

The operating lever 9 for the dispenser extends laterally outwardly from the body 1 of the dispenser. Above the path of the lever a bracket 44 is secured to the adjacent side of the dispenser body. This bracket journals the horizontal shaft 45 which is at right angles with the shaft 37. At its inner end the shaft 45 has secured thereto an abutment arm 46 which extends downwardly into the path of the dispensing lever 9 and is engaged by the lever when it is swung rearwardly. Within the bracket 44 the shaft 45 has secured thereto an abutment arm 47 adapted at certain times to be in the path of the dispensing lever 9 when swung forwardly, the shaft 45 being then shifted forwardly when the lever engages with the abutment arm 47 and is shifted rearwardly when the dispensing lever engages with the abutment arm 46.

Secured to and extending upwardly from the shaft 45 adjacent to the arm 47 is the cam lever 48 whose upper end is rounded and is in the path of the cam wing 43. When the weighted lever 41 is freed and swings downwardly, this cam wing will wipe against the end of the cam lever to swing it outwardly and thereby cause rotation of the shaft 45 to swing the abutment arm 47 inwardly into the path of the dispensing lever 9. The abutment lever 46 is weighted and upon rotation of the shaft 45 it is swung away from the vertical so that when the cam wing is released from the cam lever and the shaft is free the lever will assume its vertical position to restore the shaft and the parts thereon to normal position with the abutment arm 47 out of the path of the dispensing lever.

The front end of the shaft 45, outside of the bearing bracket 44, has secured thereto an L-shape arm 49 whose horizontal limb extends rearwardly over the bracket and pivots a pawl 50 having the beveled end 51 and the pull hook 52. A spring 53 on the arm 49 engages with the pawl and tends to swing it and hold it in upper position.

This pull pawl is adapted to engage with the pins 54 extending in axial direction from a ratchet disc 55 which is secured to the inner end of the escapement shaft 33 of the magazine structure. The ratchet pins are arranged in a circumferential row concentric with the shaft and the pins are spaced apart 45° , there being eight pins.

The pawl supporting arm 49, being secured to the shaft 45, will rotate therewith. Normally when the arm 38 is held out by the

engagement of the spring end 40 with the cups of the stack in the dispenser, and the cam wing 43 is released from the cam lever 48, the weighted lever 46 holds the shaft 45 with the pawl supporting arm 49 swung laterally with the pawl end out of operative position relative to the ratchet pins 54, as shown by dotted lines in Figures 2 and 4. However, when the spring end 40 is released, the weighted arm 41 becomes effective to apply the cam wing to the cam lever and then upon rotation of the shaft 45 the abutment arm 47 is swung into the path of the dispensing lever and the pawl supporting arm 49 is swung to bring the pawl into the operation plane of the pins 54 so that when the dispensing lever is pulled forwardly, for the purpose of dispensing a cup from the dispenser, the pawl hook will engage with one of the ratchet pins and will cause a 45° rotation of the ratchet disc so that by the corresponding rotation of the shaft 33 and the escapement fingers thereon the pusher structure P will be released by one finger for a one step advancement until stopped by the next escapement finger which will have been brought to the stop position. As has already been explained, such advancement of the push structure and the reserve cup stacks thereon will cause the end stack to be shifted on the magazine structure and into position above the dispenser into which it drops to form a continuation of the stack remaining in the dispenser. As the reserve stack drops into the dispenser it passes along the end 40 of the contact spring and thereby causes the arm 38 to be swung outwardly and the weighted lever 41 to swing upwardly so that the cam wing is withdrawn from the cam lever 48 to permit the weighted lever 46 to restore the shaft 45 and the pawl supporting arm 49 to normal position with the pawl arm out of engagement with the ratchet pins.

As the dispensing lever is now swung back to its normal position it will engage with the lever 46 to cause the shaft 45 to be shifted rearwardly to its normal position and then when the dispenser again becomes empty and the cam wing engages with the cam lever, the shaft will be again rotated to bring the pawl into operative position relative to the ratchet pins on the ratchet disc 55.

It will be noted that the stacks S, with the exception of the end stack, seat on the ribbon 29 which pulls the push structure P. The stacks are thus carried with the ribbon and kept from frictional engagement with the bar 17 and will therefore be held in upright position during shifting of the stack row by the pusher structure.

When the magazine is empty, the push structure P is pulled to its outer position and the shaft 33 is rotated to bring the end escapement finger a into horizontal position in front of the push structure, and then the magazine

is refilled with reserve cup stacks. The dispenser is also refilled with a complete stack of cups.

Briefly summing up the operation, the person desiring to obtain a cup pulls the dispensing lever 9 forwardly whereupon a cup drops from the dispenser. Where the dispenser is associated with a liquid dispensing device the lever 9 may be connected with the operating mechanism of the device to be automatically swung at the proper time to dispense a cup for receiving the dispensed liquid. While the stack in the dispenser is above the range of the spring end 40 the abutment arm 47 will be out of the path of the dispensing lever. However, as soon as the level of the top of the stack in the dispenser falls below the range of the spring end 40 the weighted arm 41 becomes defective and the cam wing 43, in its downward movement, wipes against the cam lever 48 to rotate the shaft 45 to bring the abutment arm 47 into the path of the dispensing lever when it is swung forwardly. The shaft is then shifted with the dispensing lever, and the pawl, which has been brought into operative position, engages one of the ratchet pins and the shaft 33 is rotated to release the push mechanism which will then shift the row of cup stacks in the magazine one step inwardly to discharge the end stack into the dispenser, and this end stack, when falling into position to form a continuation of the stack in the dispenser, engages the spring end 40 and swings the arm 38 to cause restoration of the connected parts to normal position and return of the shaft 45 to normal position by the engagement of the dispensing lever with the abutment lever 46 when the dispensing lever is swung rearwardly.

Upon forward swing of the dispensing lever when the dispenser needs replenishing, only the pawl mechanism and the escapement shaft 33 are operated, the power for shifting the push mechanism and the magazine cup stacks being entirely independent of the power exerted by swinging the dispensing lever, the spring operated propulsion means connected with the push mechanism by the tape 29 automatically providing all the power for shifting the magazine stack to replenish the dispenser.

The magazine structure is simple, practical and efficient and can be economically manufactured. It can be used with equal efficiency with manually operated cup dispensers, or with cup dispensers associated with liquid dispensers and automatically operated by the operation of the liquid dispensing apparatus.

Although I have shown one practical and efficient embodiment of the various features of my invention, I do not desire to be limited thereto as changes and modifications can

be made without departing from the principles and scope of the invention.

I claim as follows:

1. A replenishing magazine for cup dispensers, including the operating mechanism therefor, comprising a support for a row of cup stacks, a pusher structure movable on said support to shift said stacks thereon, a propulsion device connected with and tending to move said pusher structure, a rotatable shaft, escapement fingers offset circumferentially on said shaft and spaced longitudinally thereon for successive stop engagement with said pusher structure and for controlling the step by step advancement of said stack row by said pusher structure when said shaft is rotated, and means linked to the cup dispenser operating mechanism for rotating said shaft one step at a time at predetermined intervals relative to the operation of the cup dispenser mechanism.

2. A replenishing magazine for cup dispensers, including the operating mechanism therefor, comprising a support for a row of cup stacks, a pusher structure movable on said support to shift said stacks thereon, a spring actuated propulsion device connected with and tending to move said pusher structure, a rotatable shaft, escapement fingers offset circumferentially on said shaft and spaced longitudinally thereon for successive stop engagement with said pusher structure and for controlling the step by step advancement of said stack row by said pusher structure when said shaft is rotated, and means linked to the cup dispenser operating mechanism for rotating said shaft one step at a time at predetermined intervals relative to the operation of the cup dispenser mechanism.

3. A replenishing magazine for cup dispensers, including the operating mechanism therefor, comprising a support for a row of cup stacks, a pusher structure movable on said support to shift said stacks thereon, a spring roller mounted on said support and having a tension member extended therefrom and connected to said pusher structure, a rotatable shaft, escapement fingers offset circumferentially on said shaft and spaced longitudinally thereon for successive stop engagement with said pusher structure and for controlling the step by step advancement of said stack row by said pusher structure when said shaft is rotated, and means linked to the cup dispenser operating mechanism for rotating said shaft one step at a time at predetermined intervals relative to the operation of the cup dispenser mechanism.

4. A replenishing magazine for cup dispensers comprising a guideway for a row of cup stacks, a pusher structure movable on said guideway and engaging the outer end of said row, a spring roller mounted adjacent to said guideway, a ribbon extending

from said roller along said guideway and secured to said pusher structure to propel said structure, said stacks being seated on to be supported in upright position by said ribbon, and escapement means for controlling the movement of said pusher structure by said spring roller and ribbon.

5. The combination with a cup dispenser comprising a supporting frame for a stack of cups to be dispensed, dispensing mechanism for dispensing cups one at a time from said stack, and a dispensing lever controlling the operation of said dispensing mechanism, of a magazine structure comprising a supporting frame, a carrier structure on said frame for supporting a row of cup stacks, a propulsion device on said frame connected with said carrier structure for moving said carrier structure on said frame, restraining means on said frame for restraining movement of said carrier by said propulsion means to a step by step advancement, actuating mechanism operable by the movement of said dispensing lever to set said restraining means, and means controlled by the number of cups in said dispenser for determining the operation of said actuating mechanism by said dispensing lever.

6. The combination with a cup dispenser comprising a supporting frame for a stack of cups to be dispensed, dispensing mechanism controlling the one-by-one dispensing of cups from said stack, and a dispensing lever for actuating said dispensing mechanism, of a magazine structure comprising a supporting frame, a carrier structure on said frame for a row of cup stacks, a propulsion device on said magazine frame for said carrier structure, escapement mechanism on said magazine frame for restraining the movement of said carrier structure by said propulsion device to a step by step advancement, means whereby advancement will cause the end stack of the row to be discharged from said magazine into said dispenser, setting mechanism for said escapement mechanism operable upon movement of said dispensing lever, and means controlled by the number of cups in said dispenser for controlling the adjustment of said setting mechanism for operation by said dispensing lever.

7. The combination with a cup dispenser having cup dispensing mechanism and a dispensing lever for actuating said dispensing mechanism, of a replenishing magazine, said magazine comprising a frame for supporting a row of cup stacks, means for shifting said row on said frame, a propulsion device for actuating said shifting means, an escapement means on said frame for restraining movement of said shifting means by said propulsion means to a step by step advancement of said row, setting mechanism for said escapement means adapted to be actuated upon movement of said dispensing lever, means

automatically controlled by the level of the cup stack in said dispenser for rendering said setting mechanism operative by said dispensing lever, and means whereby each advancement of said stack will deposit the end stack of the row into said dispenser, said propulsion device operating independently of the power applied to swing said dispensing lever.

8. The combination with a cup dispenser comprising dispensing mechanism for controlling the dispensing of cups one by one from said dispenser, and a dispensing lever for actuating said dispensing mechanism, of a replenishing magazine, said magazine comprising a supporting frame, a carrier on said frame for a row of cup stacks, propulsion mechanism on said frame for moving said carrier, an escapement shaft on said frame, escapement fingers spaced longitudinally and offset circumferentially on said shaft to cooperate with said carrier structure to restrict the movement thereof by said propulsion mechanism to a step by step advancement, a ratchet member on said shaft, setting mechanism on said dispenser comprising a pawl for cooperating with said ratchet mechanism, said setting mechanism being normally out of the range of movement of said dispensing lever, and means controlled by the number of cups in said dispenser for adapting operation of said setting mechanism by said dispensing lever, operation of said setting mechanism by said lever causing setting of the escapement mechanism by said pawl and ratchet mechanism for a one step advancement of said carrier by said propulsion mechanism, and means whereby such advancement will discharge the end stack of said row from the magazine into said dispenser.

In testimony whereof I have hereunto subscribed my name at Detroit, Wayne County, Michigan.

HENRY H. OLSEN.
